UNITED STATES PATENT OFFICE.

GEORGE E. CURTISS, OF NEW BRITAIN, CONNECTICUT, ASSIGNOR TO LANDERS, FRARY AND CLARK, OF NEW BRITAIN, CONNECTICUT, A CORPORATION OF CONNECTICUT.

DESIGN FOR A DOUBLE BOILER.

Application filed April 13, 1922. Serial No. 1,724. Term of patent 14 years.

To all whom it may concern:

Be it known that I, GEORGE E. CURTISS, a citizen of the United States, residing at New Britain, county of Hartford, and State of Connecticut, have invented a new, original, and ornamental Design for Double Boilers, fully described and represented in the following specification and the accompanying drawings, forming a part of the same.

The drawing is a view in side elevation of a double boiler showing the new design, the handles being broken off.

What is claimed is:

The ornamental design for a double boiler as shown.

In testimony whereof, I have hereunto set my hand.

GEORGE E. CURTISS.
